UNITED STATES PATENT OFFICE

167,667

REVERSIBLE DRINKING VESSEL

Albert Babany, Cairo, Egypt

Application November 3, 1949, Serial No. 5,852

Term of patent 14 years

(Cl. D36—8)

To all whom it may concern:

Be it known that I, Albert Babany, a citizen of Egypt, residing at Cairo, 4 Haret el Soufi Street, Opera Square, have invented a new, original, and ornamental Design for a Reversible Drinking Vessel, of which the following is a specification, reference being had to the accompanying drawings, forming a part hereof.

Fig. 1 is a top plan view of a reversible drinking vessel, showing my new design.

Fig. 2 is a side elevational view thereof partly in vertical section.

I claim:

The ornamental design for a reversible drinking vessel, as shown.

ALBERT BABANY.
